UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed May 15, 1924. Serial No. 713,416.

To all whom it may concern:

Be it known that I, EDWIN E. BARNEY, citizen of the United States, and resident of New Rochelle, in the county of Westchester 5 and State of New York, have invented certain new and useful Improvements in Type-writing Machines, of which the following is a specification.

My present invention relates to paper feeding mechanism for typewriting machines, and its principal object is to provide new and improved mechanism of the character stated. More specifically, the object of the invention is to simplify and improve the 15 paper feeding and controlling mechanism disclosed in the patent to Barney and Barr No. 1,489,587, granted Apr. 8, 1924.

To the above and other ends which will hereinafter appear, my invention consists 20 in the features of construction, combinations of devices and arrangements of parts herein-after described and particularly pointed out in the claims.

In the accompanying drawings—

25 Figure 1 is a fragmentary transverse sectional view of a typewriter platen carriage embodying my invention, the paper feeding devices being shown in operative positions.

Figure 2 is a fragmentary plan view of 30 the carriage with the platen removed.

Figure 3 is a sectional view taken on a plane designated by the section line 1—1 in Figure 2, the paper feeding devices being shown in released positions.

35 Figure 4 is a sectional view of a detail.

As shown in the drawings, the carriage of the machine comprises an angularly disposed rear plate composed of top and bottom grooved bars 1 and 2 and connecting webs 3, thus providing an inclined rear bar. Fixed to the ends of the rear bar or plate 1—3 are forwardly extending side plates or end bars 4, the carriage comprising the rear bar and the end bars carrying a rotary cylindrical platen 5. Said carriage is adapted to travel back and forth under the impulse of a spring motor and controlled by escapement mechanism along fixed grooved guide rails 6 and 7, roller bearings 8 being 45 interposed between the guide rails and the grooved bars 1 and 2 of the carriage. Preferably the platen may be mounted on the carriage in the manner disclosed in the patent to John H. Barr #1,461,510 granted 50 July 10, 1923.

The novel paper feeding and controlling devices comprise main and secondary feed roller devices arranged to cooperate with the platen at its under side, the main feed roller devices behind the others. The machine is of the front strike variety, the types 60 striking against the front face of the platen. Said main feed roller devices comprise a pair of hub or roller sections 9 of metal extending longitudinally of the platen and 65 on which are mounted feed roller sections 10. These are preferably composed of rubber or the like, one of said hub or roller sections 9 supporting two feed roller sections 10, in the present instance, there being four 70 of such sections 10, in all. Connecting the hubs 9 is a rod section or stub shaft 11, there being also stub end shafts 12 at the outer ends of the hubs. The stubs 11 and 75 12 may be driven into the hubs 9, constituting with them a unitary shaft. Small rolls 10^a of rubber interposed between the sections 10 serve as supports for a paper deflector. Forward of the main feed roller element is a supplemental or secondary feed 80 roller element comprising cylindrical rubber sections 13 mounted in pairs on metal hub or bearing portions 14 which are carried by rod or shaft sections 15 and 15^a. The feed roller shafts 11, 12 and 15, 15^a take 85 bearings in slots or open mouthed bearing openings 16 and 17 formed in the opposite end portions of carriers or cradles 18. These carriers or cradles are in the form of arms pivoted at 19 between their ends to the outer 90 end portions of arms 20, said arms 20 terminating at their opposite ends in hubs 21 which are perforated to fit over a rod or shaft 22 secured at its ends in the end plates or bars 4 of the carriage frame. Collars 25 95 are fixed to the rod by set screws 26 and cooperate with the ends of said hubs to prevent endwise displacement of the arms 20 along their supporting rod. Said rod is secured in place on the end bars by cross pins 27 and provides a tie rod or strengthening member for the carriage frame as well as constituting a bearing for the arms 20. The pivots 19 carried by said arms are preferably 100 shouldered screws which are threaded into enlarged portions or bosses 20^a at the ends of the arms 20, these bosses serving to space the arms or carriers 18 away from the arms 20 so as to avoid friction or rubbing when the carriers or cradles turn on their pivots 19. 105 110

To support certain of the parts I provide a pair of angular bracket members arranged one near each end of the carriage and each comprising a vertical forwardly extending branch or arm 28, a horizontal forwardly extending branch or arm 29, an upright vertical portion or short neck 30 and at the top thereof an angularly disposed bar-like portion 31. Each bracket member 28-31 is secured to a web portion 3 of the rear bar by headed screws 32. The tie-rod 22 passes through bearing openings formed in the bracket arms 28 near their forward ends, an additional support for said tie rod being thus provided. Secured by screws 33 to the outer webs 3 are flat springs 34, the forward free ends of said springs being so shaped as to engage effectively with the under portions of the enlargements 20^a of the arms 20. The springs 34 press upward constantly against the arms, and their tension is thereby transmitted to the carriers 18 and the main and supplementary feed roller devices, the spring means or devices 34 tending constantly to maintain the feed roller elements 10 and 13 in spring pressed engagement with the under side of the platen 5. The sections 10 and 13 of the feed rollers protrude through cut-outs or openings 35 and 36 formed respectively in the rear and forward portions of a paper deflector or apron 37, said deflector being pivotally supported from the pivoted arms 20. To this end the deflector supporting arms 38 are pivoted at their rear ends on shouldered pivot screws 39, which are threaded into the outer faces of the bosses or enlargements 20^a of the two outside arms 20. The arms 38 extend forward and at their forward ends are provided with outwardly extending lateral bearing pins 40 which are engaged by perforations in ears 41 extending downward from the deflector 37, the deflector being thus pivotally supported at the forward ends of the arms 38. Portions of the deflector projecting rearward between the feed roller sections 10 may rest on the small supporting rolls 10^a. The deflector is constantly pressed upwardly at its forward side by spring means comprising comparatively weak wire springs 42 that are carried by headed pins 43 extending laterally outward from the arms 20. One free end portion of each spring bears against the associate hub 21 and the other end portion re-acts against a pin 44 carried by the support or arm 38. The arms of the springs 42 tend constantly to spread or separate and the re-action resulting presses upward constantly the forward portion of the paper deflector 37. The upward movement of the deflector is however limited by the pins 44 which are extended laterally inward from the arms 38 far enough to underlie the associate carriers or cradles 18, acting as stops thereagainst,

the construction being such that the upward movement of the deflector is limited by the feed roll carriers. The paper introduced at the rear is guided into the bight between the platen and the paper deflector 37 over a two-part paper table, the forward part only of said table being shown herein and numbered 45. The paper table part 45 is secured to the bar-like portions on supports 31 of the bracket members and said paper table part is formed at its forward end with fingers 46 to fit into corresponding notches or openings in the rear end of the paper deflector 37, thus blocking the opening between the two parts so that paper may not slip through.

Passing between the platen 5 and the deflector 37 at the under side of the platen the paper is advanced at the front side into the control of paper finger contrivances or guides 47. Each of these is preferably made of a single piece of sheet metal and comprises an upright portion 48 and an integral horizontal disposed portion 49. The portion 48 at its upper end above the printing line carries a pressure roll 50 which is mounted on a pivot 51 carried by the paper finger. The horizontal portion 49 is provided at its lower side with a contact device 52 which is effective to actuate line locking mechanism not shown herein. Near its ends the horizontal portion 49 is provided with pairs of clips or engaging devices 53 struck from the sheet metal of the portion 49 and which fit over a rod or rectangular supporting bar 54 which also carries an inset platen scale 55. Said bar 54 extends along the platen at its front side and below the printing line, and the contrivances or fingers 47 are slidably mounted on said bar. Screw stops 56 secured to the end portions of the bar 54 limit the outward movement of the paper fingers 47, of which there are preferably two. In order to facilitate the removal of the paper fingers from the bar, the latter near its outer ends is cut away at the under side, as indicated at 57, enabling the paper finger when slid down to the notch or cut-away 57 to be unhooked or pulled forward, so as to be readily removed without displacing the bar itself, as graphically shown in Fig. 4, which illustrates the left-hand paper finger in process of removal. Preferably the inner clip at the lower side of each part 49 is straight and not hook shaped as are the other clips 53. The straight clip 53 facilitates ready removal of the paper finger, permitting the cut-away to be shortened, since it is only necessary that the lower hooked clip 53 be opposite to it to enable the paper finger to be slipped off the bar. The paper finger bar 54 and the paper fingers are pivotally mounted, and to this end the bar 54 is provided near its outer ends with rearwardly extending lugs or tongues 58, said lugs being

perforated laterally, as indicated at 59, to fit over and engage with bearing pins 60 carried by the forward end portions of the bracket arms 29 and extending laterally inward therefrom. The bar 54 is adapted to receive rotary movements on the pivotal centers or pins 60 so as to swing the paper fingers towards and away from the platen. The free ends of flat springs 61 overlie the rear ends of the tongues 58, said springs being secured by screws 62 to the tops of the bracket arms 29 and extending forward towards the tongues against which they press constantly downward, tending thereby to maintain the paper fingers in co-operative engagement with the platen. The paper fingers are adapted to be released simultaneously or concurrently with the feed rollers, as hereinafter explained, but may also be released separately and independently, and to this end the right-hand end of the bar 54 is provided with a paper-finger release-key in the form of an arm 63, said arm being provided at its rear with a lateral extension 64 disposed behind the bar 54 and secured thereto by headed screws 65. The arm 63 extends forward over the top of the bar and terminates in a finger piece or key proper 66. By depressing this key 66 the springs 61 may be overcome and the paper fingers 47 swung forward away from the front face of the platen without disturbing the feed rollers.

The various paper feeding devices are released preferably by relieving the tension of their respective springs. The releasing devices comprise a rod or rock shaft 67 which bears in bracket arms 28, said rock shaft being arranged behind the tie rod 22. The left-hand end portion of the shaft 67 is extended leftward through the left-hand end bar 4, and is preferably controlled by key actuated devices as disclosed in the aforesaid Patent No. 1,489,587. Just outside said left-hand end bar the shaft 67 has rigidly secured to it by a screw 68 a crank arm 69, the outer or free end whereof is pivotally connected at 70 with a lever or toggle member 71 which extends upward and curves forward over the platen axle, said member terminating in a laterally bent finger key 72. The lower end of the lever member 71 below its pivotal connection 70 is pivotally connected at 73 with a link or toggle member 74 which is pivoted at 75 on the outer face of the end bar. The pivot 75 is preferably a flanged eccentric device which is rotatably adjustable on a headed clamping screw 76, which passes through the eccentric 75 and is threaded into the end bar 4. To prevent buckling or bending of the shaft 67 an arm or tongue 77 is provided to overlie it near its middle portion, said arm being secured by screws 78 to the central web 33. Endwise displacement of the shaft 67

is prevented by collars 79 which are secured to said shaft inside the bracket arms 28 by set screws 80. The shaft 67 is provided with releasing devices in the form of crank members, there being two outer double crank members 81 and a middle single crank member 82. The middle crank member 82 has a hub 83 which fits over the shaft 67 and is secured thereto, as by a pin 84. At its outer or free end the crank arm 82 carries a laterally extending projection or pin 85 which overlies the associate spring 34 and is adapted to depress the same when the shaft 67 is rocked rearward. Each of the double crank members 81 comprises a hub 86 pinned or otherwise secured to the shaft 67 and from which extends a rearward crank arm 88 and an oppositely projecting forward crank arm 89. The rearward crank arm carries a pin or projection 90 which overlies the associate spring 34, while the front arm underlies the associate spring 61. The normal relationship of the paper feeding and controlling devices to the platen is illustrated in Figure 1.

When the release key 72 is actuated and the shaft 67 is rocked, the pins 85 and 90 will be swung downward flexing the springs 34 downward, and rendering them inoperative. At the same time the crank arms 89 will be swung upward, flexing the springs 61 upward sufficiently to render them inoperative. As a result, the main and secondary feed rollers 10 and 13 will be freed from the control of their springs and released, due to the downward swinging of their supports 20 under the force of gravity. Concurrently the paper fingers will be released owing to the releasing and consequent gravitational forward movement of the supporting bar 54. Because of the releasing of the carriers 18 from the control of the springs 34, the paper deflector 37 is also relieved of the pressure of its springs 42, these being of course too weak to oppose the weight of the feed roller mechanisms. The released position of the paper feeding and controlling devices is shown in Figure 3.

My invention comprises comparatively few parts, considering the results obtained, and the parts are effective in operation and easy in action. By said invention there is provided a platen and a feed roller in combination with a pressure device constantly tending to maintain said feed roller in co-operative engagement with the platen, and releasing means operative directly on said pressure device. The pressure device in the present instance comprises a plurality of flat springs, and the releasing means comprise a corresponding plurality of key controlled pins co-acting directly with the springs to flex them and thus relieve the feed roller of pressure. This construction

is effective on both the main and secondary feed roller mechanisms. Also, the paper fingers and the paper deflector are similarly controlled and released by flexing their pressure springs so as to relieve the paper fingers and paper deflector of the spring pressure to which they are normally subjected. The springs for the feed rollers and for the paper fingers are oppositely acting, the former pressing upward and the latter exerting a downward pressure, and, consequently, oppositely acting releasing devices in the form of duplicate crank arms are provided to act oppositely on the springs.

15 Various changes may be made without departing from my invention.

What I claim as new and desire to secure by Letters Patent is:—

1. In a front strike typewriting machine, the combination of a platen, a platen carrier, a rod thereon, arms pivoted on said rod, cradles pivoted on said arms, parallel feed rollers carried by said cradles at their opposite ends and co-operating with the platen at its under side, springs constantly pressing against said arms, and means acting directly against said springs to flex them and permit said feed rollers to drop from the platen through gravity.

20 2. In a typewriting machine, the combination of a platen, a platen carrier, a rod thereon, arms pivoted at their ends on said rod, carriers pivoted between their ends at the opposite ends of said arms, parallel feed

25 rollers carried by said carriers at their opposite ends, separate springs constantly pressing against said arms, and releasing means comprising separate devices each acting directly against one of said springs.

30 3. In a typewriting machine, the combination of a platen, a feed roller, a paper finger, spring means for maintaining said feed roller in spring pressed engagement with the platen, separate and independent

35 spring means for maintaining said paper finger in spring-pressed engagement with the platen, and releasing means comprising independent devices acting directly on said independent spring means to relieve the

40 pressure on said feed roller and said paper finger.

4. In a typewriting machine, the combination of a platen, a feed roller, a paper finger, spring means for maintaining said feed roller and said paper finger in spring pressed engagement with the platen, releasing means acting directly on said spring means to relieve the pressure on said feed roller and said paper finger, and a key connected to said paper finger and effective to release it independently.

5. In a typewriting machine, the combination of a feed roller, a paper finger, a paper deflector through which said feed roller protrudes to engage with the platen,

spring means for maintaining said feed roller, said paper finger, and said deflector in spring pressed engagement with the platen, said spring means comprising separate and independent springs for said feed roller, said paper finger and said deflector, and releasing fingers acting directly on the separate springs of said feed roller and said paper finger to relieve the pressure on said feed roller, said paper finger, and said paper deflector.

6. In a typewriting machine, the combination of a feed roller, a paper finger, a paper deflector through which said feed roller protrudes to engage with the platen, spring means for maintaining said feed roller, said paper finger, and said deflector in spring pressed engagement with the platen, a release key, and oppositely acting devices controlled thereby to engage directly with and render said spring means ineffective, said devices being normally disconnected from said spring means and being effective to act directly thereagainst to flex the same.

7. In a typewriting machine, the combination of a feed roller, a paper finger, a paper deflector through which said feed roller protrudes to engage with the platen, separate springs for said feed roller, said paper finger, and said paper deflector, and releasing means comprising projections acting directly on the separate springs for the feed roller and the paper finger to afford a release of said feed roller, said paper finger and said deflector.

8. In a typewriting machine, the combination of a platen, a carriage frame, a tie rod thereon, arms pivoted on said tie rod, cradles pivoted between their ends on the end portions of said arms, feed roller shafts bearing on the end portions of said cradles, sectional feed rollers on said shafts, a paper deflector pivoted on said carriage frame and provided with openings through which said sectional feed rollers protrude, a paper finger bar pivoted on said carriage frame, paper fingers slidably mounted on said bar, springs acting against said bar to press said paper fingers towards the platen, other springs acting against said paper deflector to press it towards the platen, other springs one for each of said arms to apply pressure to said feed rollers, and key controlled releasing devices acting directly on all of said springs to release respectively the paper fingers, the paper deflector, and the feed rollers concurrently.

9. In a typewriting machine, the combination of a platen, a carriage frame, a tie rod thereon, arms pivoted on said tie rod, cradles pivoted between their ends on the end portions of said arms, feed roller shafts bearing on the end portions of said cradles, sectional feed rollers on said shafts, a paper

- deflector pivoted on said carriage frame and provided with openings through which said sectional feed rollers protrude, a paper finger bar pivoted on said carriage frame, 5 paper fingers slidably mounted on said bar, springs acting against said bar to press said paper fingers towards the platen, other springs acting against said paper deflector to press it towards the platen, other springs 10 one for each of said arms to apply pressure to said feed rollers, key controlled releasing devices acting directly on all of said springs to release respectively the paper fingers, the paper deflector, and the feed rollers concurrently, and a key secured to said paper finger bar for separately releasing said paper fingers.
10. In a typewriting machine, the combination of a platen and a co-operating 20 feed roller device comprising metal hubs, feed roller sections on said hubs, and stub shaft portions driven into said hubs and constituting therewith a unitary shaft member.
- 25 11. In a typewriting machine, the combination of a platen, a co-operating main feed roller device, and a supplementary feed roller device also co-operative with the platen, each feed roller device comprising 30 metal hubs, feed roller sections on said hubs, and stub shaft portions driven into said hubs and constituting therewith a unitary shaft member.
- 35 12. In a typewriting machine, the combination of a platen; a co-operating feed roller device comprising metal hubs, feed roller sections on said hubs, and stub shaft portions driven into said hubs and constituting therewith a unitary shaft member; 40 rubber supporting rolls on said hubs between said feed roller sections; and a paper deflector partly supported by said rolls.
- 45 13. In a typewriting machine, the combination of a platen, a carriage frame, supporting arms pivoted on said frame, carriers pivoted on said supporting arms, feed rollers mounted on said carriers, other arms pivoted on said supporting arms, and a paper deflector pivoted on said other arms.
- 50 14. In a typewriting machine, the combination of a platen, a carriage frame, supporting arms pivoted on said frame, carriers pivoted on said supporting arms, feed rollers mounted on said carriers, other arms pivoted on said supporting arms, and a paper deflector pivoted on said other arms.
- 55 15. In a typewriting machine, the combination of a platen, a carriage frame, supporting arms pivoted on said frame, feed roller arms pivoted between their ends on said supporting arms, parallel feed rollers mounted on said feed roller arms, paper deflector arms pivoted at their ends on said supporting arms co-axially with said feed roller arms, and a paper deflector mounted on said deflector arms.
- 60 16. In a typewriting machine, the combination of a platen, a carriage frame, supporting arms pivoted on said frame, feed roller arms pivoted between their ends on said supporting arms, parallel feed rollers mounted on said feed roller arms, paper deflector arms pivoted at their ends on said 65 supporting arms co-axially with said feed roller arms, a paper deflector mounted on said deflector arms, springs carried by said supporting arms acting against said paper deflector, and separate feed roller springs supported on said carriage frame and acting against said supporting arms.
- 70 17. In a typewriting machine, the combination of a platen, a carriage, a rod or bar thereon, and a paper finger provided with clips whereby said finger is slidably supported on said rod or bar, said rod or bar being cut away near one end to facilitate removal of said paper finger without displacing said rod or bar.
- 75 18. In a typewriting machine, the combination of a platen, a carriage, a rectangular bar supported therefrom, a one-piece sheet metal paper finger provided with clips to slidably engage said bar, said bar being provided with a notch or cut-away and certain of said clips being so formed as to facilitate removal of the paper finger from the bar when brought opposite to said notch.
- 80 Signed at the borough of Manhattan, city of New York, in the county of New York and State of New York, this 13th day of May, A. D. 1924.
- 85 100 EDWIN E. BARNEY.
